WILLIAM H. SCHNEIDER, OF MILWAUKEE, WISCONSIN

FAN

Application filed October 17, 1921, Serial No. 508,276. Renewed March 25, 1929.

This invention relates to fans and is particularly directed to a fan for controlling the temperature in the circulating or cooling system of an internal combustion engine.

5 Objects of this invention are to provide means for normally maintaining a proper temperature of the circulating medium; to provide means whereby this temperature may be varied to meet various conditions 10 under which the engine works; and to provide means which may be directly controlled by the temperature of the circulating medium.

Further objects are to provide a fan for an 15 internal combustion engine with the blades of the fan so arranged that their angular position may be varied to thereby vary, control, or reverse the flow of air past the engine and through the radiator; to provide such a 20 fan in combination with means for controlling the angular setting of the blades; and to provide means which may be used in conjunction with the usual automobile equipment.

25 Further objects are to provide a fan in which the blades may have their angular position varied by remote controlled means in which the blades are so proportioned that their angular position may be varied by the 30 expenditure of a small amount of energy; to provide a fan and control means therefor, whose parts, although adequately housed, may be readily inspected, renewed or repaired.

35 Embodiments of this invention are shown in the accompanying drawings, in which:

Figure 1 is a sectional view of the fan.

Figure 2 a partial sectional view of an automatic control for such fan.

40 Figures 3 and 4 a side and end elevation respectively of a manual control for the fan.

Figures 5, 6, and 7 partial, transverse, sectional views of a four-bladed, three-bladed 45 and two-bladed fan respectively.

Figure 8 a detail of the mechanism for setting the blades at the desired angularity.

Figures 9 and 10 details of the joints for the ends of the flexible connector and housing therefor, at the point where the flexible

connector joins the control means and fan respectively.

Fig. 11 is a plan view of the fan showing one of the fan blades as it appears longitudinally of its axis.

The fan comprises an annular member 1 which is provided with integrally formed tubular members 1^a extending both inwardly and outwardly through the wall of the annular member 1. These tubular members have a separate and distinct part 1^b (see Figures 5 and 6) which may be formed integrally with the adjacent angularly arranged tubular member, or may be carried by a bracket extending inwardly from the annular member 1 (see Figure 7). These tubular members 1^a and 1^b provide a space between them for a purpose hereinafter to be described. Each face of the annular member is provided with an overhanging flange 1^c concentrically arranged with respect to the body of the annular member 1, and with inwardly projecting lugs 1^d provided with apertures 1^e. The annular member 1 is carried by means of a bell-shaped member 2, 61 having a tapered or conical portion 2^b and integrally formed pulley 2^a which is provided with an internal bushing 15.

70 The device is rotatively supported upon a spindle 14 which is provided at its outer end with an integral collar 14^a, and at its inner end with reduced portion adapted to be passed through an apertured bracket 14^b carried by the internal combustion engine. The 75 projecting portion 14^b of the spindle is threaded and is adapted to receive a nut 14^c so that the bracket 14^b may be clamped between such nut and the shoulder 14^d of the spindle, thereby rigidly securing such spindle in operative relation to the engine and to 80 the radiator in the usual and well-known position. The spindle is further provided with an outwardly projecting reduced and threaded portion 14^a upon which is screwed 85 an elongated cap member 9 for a purpose hereinafter to be described. The front portion of the annular member 1 is closed by a 90 conical cap 16, such cap and the member 2^b being both properly centered by means of 95 their respective flanges 16^a and 2^c, suitable 100

rivets or bolts 17 passing through these flanges and the apertures 1^h in the annular member 1. In this manner an enclosed hollow hub provided with a unitarily formed pulley is rotatively mounted upon a rigidly positioned spindle.

A series of spindle members or shafts 3 are passed thru the tubular members 1^a and 1^b and through gears 5 positioned between such 10 tubular members, the gears being preferably rigidly secured to the spindles or short shafts 3 by means of pins 5^c. The outer or projecting ends of the short shafts 3 are provided with flat enlarged faces 3^a, spaced 15 slightly apart and adapted to receive the fan blades 18 between them, such blades being held in place by suitable rivets 3^a. These blades, as will be noted from an inspection of Figure 5, are equally spaced about the 20 extended axis of the shaft 14 and are preferably ribbed to give, respectively, a perfect balancing about the axis of the shafts 3 and the necessary rigidity. The gears 5 are provided through a portion of their peripheries 25 with ordinary spur teeth 5^a and are adapted to mesh with a circularly formed rack 4^a. The rack 4^a has integrally formed hubs 4 which terminate at their outer ends in cup-shaped enlargements 4^b and 4^c. This circular rack is carried by ball-bearings consisting of the balls 4^d, the cup-shaped bearings 30 4^b and 4^c, and the conical members 8^c, such latter being carried upon a shaft 8, axially arranged with respect to the entire fan. 35 These ball-bearings and rack are held in position upon the shaft 8 by means of a nut 8^d of such shaft. By having the rack mounted upon ball-bearings, it will rotate with the fan, and therefore the intermeshing teeth 40 will be relieved of a large amount of wear. The solid portion of the gears 5 form stops to limit the angle through which the blades may be turned. It will be seen that when the shaft 8 is moved axially of the fan 45 through the rigidly positioned spindle 14, that it moves the rotatively mounted circular rack 4^a, and simultaneously partially rotates all of the blades about their central axes. In this manner the flow of air, both as 50 to velocity and direction, may be controlled by the position of the shaft or spindle 8.

The inner end of the spindle 8 has attached thereto a flexible member, such for example as a spring wire 12, by means of a shell nut 55 8^e, the nut having a central aperture through which the wire 12 projects. Figure 9 shows in detail this construction. A convenient way of insuring the retention of the wire 12, is to bend its end 12^a into a loop and place a 60 drop of solder thereon so as to form a globular nob or terminal 12^b, greatly in excess of the size of the aperture through the shell nut 8^e. This nut is provided with internal threads meshing with external threads 65 formed upon the inner projecting terminal

of the shaft 8. If desired, an aperture 8° may be formed at any point in the shaft 8 and may receive temporarily a pin to aid in holding the shaft against rotation, while the nuts 8^e and 8^d are screwed into place. The elongated 70 cap 9 receives the housing or flexible sheath 11 of the wire or member 12. This sheath 11 has secured thereto a thimble 11^a, provided with a terminal flange 11^b adapted to engage the interior of the member 9, and threaded 75 upon its exterior or projecting portion to receive a clamping nut 11^c.

From the construction thus far described, it is apparent that by shifting the control member 12 axially through its guiding and enclosing sheath 11, the flow of air may be controlled both as to its speed and direction, and that such control may be had from a remote point. Various types of control may be used, two of which will be described here-with.

One form of control, such as is shown in Figure 2, comprises a thermostatic device in the form of a metal bellows 6. This bellows or thermostatic device is positioned within a casing 7ⁱ by means of an annular threaded member 7^e, such member serving to close the otherwise open end of the casing 7ⁱ. The inner end of the thermostatic member 6 is provided with an outwardly projecting pin 6^b, whose extreme end 6^c is threaded. This pin is projected through an apertured boss on the member 7ⁱ and is retained in place by means of a nut 6^d. The casing is secured in any desired position by means of the flange 7, 90 which latter is provided with a series of holes 7^h to receive attaching bolts. The outer end of the casing 7ⁱ is provided with a threaded boss 7^a, having an aperture through which a spindle 6^a, secured to the outer end of the thermostatic member 6, projects. The outer end of this spindle 6^a is attached to the inner end of the control wire or member 12 by means of a nut 6^d in a manner similar to that previously described. This construction is shown in detail in Figure 10. An elongated cap 10 is threaded to the projecting boss 7^a and is internally shouldered at 10^c to receive one portion 7^c of a packing gland, the other portion being provided by the conically recessed outer end of the boss 7^a. The packing 7^b is positioned between the portions of the packing glands and is forced into intimate contact with the rod 6^a when the elongated cap 10 is screwed into 110 position. The inner end of the sheath 11 for the wire 12 is secured to the outer end 10^b of the member 10 in a manner similar to that previously described in connection with the member 9.

In this device a portion of the circulating cooling medium for the internal combustion engine is passed through the casing 7ⁱ, to thereby transmit to the thermostatic member 6 substantially the temperature of the 115 120 125 130 135

cooling medium of the engine. The member 6 is hermetically sealed and carries therein any desired expanding material, such as is commonly employed in this type of thermostatic device.

The operation of the device is as follows: When the temperature of the cooling medium rises, the thermostatic device 6 expands in the direction indicated by the arrow in Figure 2, and thereby pushes the wire 12 outwardly through its guiding sheath 11. The wire in turn, pushes the spindle or rod 8 axially of the fan, and causes partial rotation of the gears 5. This rotation of the gears is transmitted through the spindles 3 to the fan blades and thereby changing their angular setting to increase the flow of air produced by the rotation of the fan. In this manner an increased quantity of air is drawn through the radiator, if such is employed, and is projected against the engine. If, however, the temperature of the cooling medium should fall below that required for efficient operation of the engine, the reverse action takes place and the fan blades are given a lesser angle, thereby decreasing the flow of air and consequently allowing the temperature of the system to rise to the desired point. Under extreme conditions, as when starting during cold weather, the fan blades are reversed so as to withdraw the warmer air from under the hood and pass it through the radiator, thereby securing more rapid rise of temperature in the system with resulting improved efficiency.

It may be found desirable under certain conditions to provide a manual control for the setting of the fan blades. Under these conditions, the device illustrated in Figures 3 and 4, is employed. The wire 12 extends into a casing 13, and its sheath 11 is secured to such casing in a manner similar to that previously described. The inner end of the wire is secured to a lever or member 13^a, rigidly carried upon a rock shaft 13^b, such shaft extending at one end outwardly through the wall of the outer casing 13. A manually operable lever 13^a is rigidly secured to the projecting portion 13^b and the rock shaft, and is provided with a pointer to indicate the setting of the fan blades, such setting being conveniently marked upon the curved face 13^c of the casing 13.

It will be seen that a fan has been provided for cooperation with an internal combustion engine to accurately control the temperature of the circulating cooling medium, to thereby secure increased efficiency for the engine.

It is to be noted that under certain conditions it is difficult for the radiator to carry away and radiate the large quantity of heat given it by the circulating medium. Under these conditions, the setting of the fan blades is such as to increase the flow of air and se-

cure the desired radiation and the corresponding desired temperature of the cooling medium. Under other conditions, it is desirable to conserve the heat of the system, and this is readily accomplished by decreasing the angular setting of the fan blades. Under extreme conditions, it may be desirable to pass the heated air surrounding the engine outwardly through the radiator. This is readily accomplished by reversing the flow of air by a suitable angular setting of the fan blades.

I claim:—

1. In combination, a rotary fan comprising a body portion, having pivotally mounted radial blades; an automatic controlling member remotely positioned with respect to said fan, and including a casing; a flexible, non-extensible member projecting therefrom; means within said casing for causing said non-extensible member to move axially; a sheath surrounding said non-extensible member; and means for operatively connecting said non-extensible member and said blades to transmit controlling motions of said non-extensible member to said blades, to thereby automatically vary the angular setting of said blades.

2. A rotary fan comprising a hollow hub, an apertured support for rotatively carrying said hub, a rod slidably mounted in said apertured support and extending into said hub, a series of spindles positioned within said hub and extending outwardly therefrom, gears carried by said spindles, a freely rotatable rack mounted on said rod and adapted to mesh with said gears, and a series of blades carried by said spindles, whereby the angular setting of said blades may be controlled by the axial motion of said rod.
